UNITED STATES PATENT OFFICE.

WILLIAM M. MANSELL, OF FORT SMITH, ARKANSAS.

WHISTLE.

Application filed June 7, 1926. Serial No. 114,334.

My present invention has reference to a whistle which may be employed as a warning signal on automobiles, an alarm, or as a musical instrument.

5 In carrying out my invention it is my purpose to produce a whistle that is operated by a fluid under pressure, such for instance, as the exhaust gases from an internal combustion engine, and in which the device includes a pipe or cylinder having its mouth coupled with the engine exhaust, and the passage of gas thereinto controlled by a valve operated in a novel manner from a convenient point in the automobile, and also in which a spring influenced plunger is arranged in the pipe or cylinder and movable to different positions therein by means arranged in close proximity to the valve operating means, the movement of the plunger 10 serving to increase the volume of sound at the pleasure of the operator, and as the sound thereby becomes deeper the same may be tuned to a variety of notes.

To the attainment of the above broadly stated objects and many others which will present themselves as the nature of the invention is better understood the improvement resides in certain novel features of construction, combination and operative association 25 of parts, a satisfactory embodiment of which is disclosed by the accompanying drawings.

In the drawings:

Figure 1 is a top plan view of my improvement.

30 Figure 2 is a plan view of the whistle or flageolet.

Figure 3 is an approximately longitudinal central view therethrough.

Figure 4 is an enlarged side elevation at 35 the mouth end of the whistle.

Figure 5 is a sectional view on the line 5—5 of Figure 3.

Figure 6 is a similar view but showing the valve open.

40 Figure 7 is a perspective view of the valve.

Figure 8 is a top plan view on an enlarged scale to illustrate the operating levers and the mount therefor.

Figure 9 is a sectional view on the line 45 9—9 of Figure 8.

Figure 10 is a sectional view on the line 50 10—10 of Figure 8.

Figure 11 is a fragmentary perspective view to illustrate the connection between 55 the valve actuating lever and the link associated therewith.

Figure 12 is a sectional view approximately on the line 12—12 of Figure 10.

In Figure 1 of the drawings I have illustrated the improvement in connection with the exhaust manifold of an internal combustion engine for an automobile, but it is, of course, to be understood that I do not wish to be restricted to this precise application of my invention, as the whistle may be operated by any fluid under pressure.

In the drawings the numeral 1 designates the exhaust pipe of an internal combustion engine, the same having attached thereto a coupling 2, and screwed in this coupling there is the mouth end of the cylindrical resonator 3 of the improvement. The cylinder 3, at its mouth end, has secured therein a block 4 provided with an opening 5 at one end thereof, the said opening forming the throat portion of the cylinder. The sound emitting aperture or lip for the cylinder is arranged directly to the rear of the block 4 and is indicated by the numeral 6. Movable on the inner face of the block 4 there is a valve plate 7. The valve plate is provided with an elongated opening 8 through which passes the stem of a headed element 9 that is screwed in the block, and above the opening 8 the valve plate is provided with a transverse opening 9 designed, when the valve plate is moved to one position, to register with the opening 5. The second or outer end of the valve plate is extended through the orifice 6 and has loosely passed 90 therethrough one end of a crank lever 10. The crank lever has its central and straight portion journaled on a shaft that is supported in suitable bearings 11 on the top of the casing, and surrounding the portion of the crank shaft 10 there is a coil spring 12 that has one of its ends contacting the said crank shaft and its other end secured to one of the bearings 11. The crank shaft has an outer eye portion 13 to which is connected 100 a flexible element 14.

In the cylinder 3 there is a plunger 15. Secured to the plunger and passing through the rear and closed end 16 of the cylinder there is a rod 17. Surrounding the rod and exerting a tension between the plunger and the said closed end 16 of the cylinder there is a light helical spring 18. The spring normally retains the plunger in the position illustrated in Figure 3 of the drawings so that the said plunger is normally arranged 110 in close proximity to the lip or aperture 6.

The face of the plunger confronting the block 4 is dished, as at 19, and the closed end 16 of the cylinder has spaced apertures therethrough. Connected to an eye on the outer end of the rod 17 there is a rod or flexible element 20.

On the dash board or on the floor board at the front of the automobile to which the whistle is attached there is a plate 21, which is preferably round in plan. The plate has a central cross member 22 provided with a lateral extension 23 that has its outer end disposed at an angle, widened and bifurcated to provide spaced arms 24. Passing through a threaded opening in the outer arm there is a threaded binding element 25. The arm is preferably provided with a compressible facing, and these arms 24 are designed to receive therebetween the instrument board 26 of the automobile. As previously intimated, the plate 21 may be secured at any desired plate in the automobile.

The upper edge of the rounded plate 21 is provided with spaced notches 27, and any one of these notches is designed to be engaged by a spring influenced dog 28 on the lower face of a lever 29. The lever is pivoted, as at 30, to the under face of the supporting plate 21. The lever is preferably integrally formed with upstanding lugs 31, and between these lugs there is pivoted, as at 32, the bent or offset portion of a second lever 33 which is disposed directly over the lever 29. The pivot 32 passes through one of a plurality of openings in the lever 33, and the end of the lever, adjacent to its said pivot 32, has secured thereon an angle bracket 34. As a matter-of-fact, the outer end of the lever 33 may be bifurcated instead of being provided with the removably secured bracket, and the bifurcated end of the said lever has elongated slots 35 therethrough. These slots are designed to receive therethrough laterally extending lugs 36 on the reduced end 37 of an arm 38. The arm is pivotally supported between the upstanding lugs 40 on the cross bar 22 of the supporting plate 21. The outer end of the arm is connected to the element 14.

Loosely connected to the lever 33 there is a link 41. This link has an offset end which is pivotally secured to an angle or upstanding flange 42 on the offset end of a plate 43. The plate is pivoted, as at 44, to a lug 45 on the cross bar 22. The plate 43 has passed therethrough the shanks of a pair of bolt members 46, the said shanks also passing through one pair of equidistantly spaced apertures 47 on a second plate 48. Nuts 49 are screwed on the bolts 46, and the outer plate 48 is connected to the element 20.

The spring influenced crank lever 10 for the valve plate 7 will initially draw on the element 14 to swing or cant the arm or plate 38, and thereby swing the outer end of the

lever 33 at an outward angle with respect to the lever 29. A pressure on the lever 33 in the direction of the lever 29 will swing the arm or plate 38 in a second direction, causing the same to draw on the element 14 to operate the crank shaft and raise the valve plate to what may be termed open position, or to bring its opening 9 into register with the opening 5 in the block 4, so that the exhaust gases passing into the mouth of the cylinder will create a sound in the well known manner. Now by swinging the lever 29 together with the lever 33, a pull will be exerted upon the element 20 to arrange the plunger 19 in desired positions in the cylinder 3. This movement of the plunger permits of the gases flowing to determined extents into the cylinder 3 and being resisted by contact with the plunger will from thence be redirected and find an outlet through the orifice 6 so that compound notes will be produced and sounded. It will be apparent that with little practice a person can so manipulate the levers as to cause the instrument to play various tunes.

It is believed that the foregoing description when read in connection with the accompanying drawings will fully set forth the simplicity and advantages of my improvement to those skilled in the art to which such inventions relate, but it is, of course, to be understood that I do not wish to be restricted to the precise details of construction herein set forth and hold myself entitled to make all such changes therefrom as fairly fall within the scope of what I claim, providing, of course, that such changes do not depart from the spirit or sacrifice any of the advantages of the invention.

Having described the invention, I claim:

1. A whistle, including a cylinder designed to have its mouth attached to the exhaust pipe of an internal combustion engine, said cylinder having a block partly closing the mouth thereof and having an orifice adjacent the block, a slideable plate on the block, having an opening therethrough, a spring influenced crank shaft engaging the valve plate for normally holding the same in one position, means for swinging the crank shaft to move the valve to a second position to open the throat of the cylinder, a spring influenced plunger in the cylinder, said plunger having a concavity at the face thereof adjacent the block and means for moving and holding the plunger in varying positions in the cylinder.

2. A whistle, including a cylinder, having a throat end designed to be attached to a conductor for fluid which is under pressure, said cylinder having a block on the said throat thereof, partly closing the same,

and having an orifice at the rear of the block, a slideable valve plate guided on the block, and having an opening therethrough, a spring influenced crank shaft normally influencing the valve plate to bring the opening thereof away from the opening between the block and mouth of the cylinder, a spring influenced plunger in the cylinder, flexible elements connected to the crank shaft and to the plunger, a round support plate having one of its edges notched, a forked bracket on the support, having a binding element associated therewith, a lever pivotally secured to the support plate, 10 a spring influenced plunger thereon for engaging in the notches of the said support plate, a second lever disposed above and pivotally associated with the first mentioned lever, an arm pivotally secured on the support plate, loosely connected with the last mentioned lever and having its outer end connected with the flexible element of the crank shaft, a link loosely connected to the last mentioned lever, a plate pivotally secured on the support plate having an offset end to which the link is loosely connected, a second plate adjustably secured on the first mentioned plate and said second plate being connected to the flexible element for the plunger. 15

In testimony whereof I affix my signature.

WILLIAM M. MANSELL.
